DRINKING TUBE AND GLASS CLAMP

Clyde C. Smith, Kokomo, Ind.

Application June 12, 1945, Serial No. 599,073

6 Claims. (Cl. 65—65)

1

This invention relates to an anchorage clip suitable for detachably securing a drinking tube to a drinking glass.

The chief object of this invention is to provide a clip that can be readily applied to a tube and glass for securing one to the other so that drinking from the glass by a sick or bedridden person is facilitated.

The chief feature of the invention, in addition to its simplicity, resides in the fact that it is non-sustainable on either the tube or the glass but requires both for connection to the same and for anchorage purposes; in other words, the clip is not independently anchored to the glass or tube and to the tube or glass respectively and successively.

Other objects and features of the invention will be set forth more fully hereinafter.

The full nature of the invention will be understood from the accompanying drawing and the following description and claims:

In the drawings,

Fig. 1 is a perspective view of a drinking glass and tube with the clip rigidly connecting same together.

Fig. 2 is a perspective view of the clip.

In the drawings, 10 indicates a conventional drinking glass having side wall 11 with exterior surface 12, interior surface 13 and top edge 14. 15 indicates the tube bottom portion, and 16 the mouthpiece portion, herein shown at an angle to the former.

The clip includes two, substantially parallel, appreciably spaced legs 17, which at the lower free ends may turn outwardly as at 18, if desired. Extending towards each other from the upper ends of the legs as at 19 are the arms 20 which lie in substantially the same horizontal plane as the glass rim 14 and angle toward the center of the glass.

Each arm at its inner end terminates in an approximate half-loop or semi-circular portion 21, the two preferably but not necessarily lying immediately adjacent each other and one above the other. Herein, by way of example only, a plane common to both legs is also tangent to the mid-portions of the half loops 21 but can be parallel to such a tangent plane depending upon the arm angularity and the loop radius.

Extending upwardly from the other end of each half-loop is an arm 22 that extends toward the aforesaid plane or planes. Preferably, but not necessarily, these arms are parallel and may be approximately as long as the legs. The upper

2

ends of the arms 22 are connected by a half-loop 23.

In the preferred form the last-mentioned loop-arm connection lies between the aforesaid tangent plane and a parallel plane passing through the junctions of the half-loops 21 and the lower ends of arms 22. Note also half-loop 23 faces oppositely relative to half-loops 21.

The three elements may be associated together 10 by any one of several methods, the easiest being as follows. The clip is applied to the top edge 14 of the glass or tumbler with arms 20 resting on the edge and with loops 21 extending inwardly of the glass and legs 17 bearing on the glass exterior 12. The tube portion 15 then is passed between the loops and glass interior 13 and forced downwardly as far as desired or required. While this is accomplished the half loops 21 are forced inwardly of the glass wall and the half-loop 23 also is brought inwardly, as it were. The tube then is clamped to the glass.

To disassociate the parts, the easiest method is to grasp the tube and arms 22 and pull upwardly on both. When legs 17 are free of the glass, or tube 15 passes above edge 14, the three parts are simultaneously disassociated.

While the invention has been illustrated and described in great detail in the drawing and the foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

- 40 1. An anchoring flexible clip for the purpose described including in combination a pair of exterior wall engaging legs, an arm extending from each and inwardly toward the other arm, each arm terminating in an arcuate portion, the arcuate portions being similarly directed, upwardly directed arms at the other ends of the arcuate portions, and an oppositely directed arcuate portion connecting the other ends of the upwardly directed arms.
- 45 2. A clip as defined by claim 1 wherein the upwardly directed arms are directed towards a plane common to the longitudinal axes of both legs.
- 50 3. A clip as defined by claim 1 wherein the legs are substantially parallel.
- 55 4. A clip as defined by claim 1 wherein the in-

wardly directed arms are initially directed angularly of each other.

5. A clip as defined by claim 1 wherein the first mentioned arcuate portions are superposed and positioned immediately adjacent each other.

6. A clip as defined by claim 1 wherein the first mentioned arcuate portions are superposed and positioned immediately adjacent each other, the first mentioned arms being initially directed angularly of each other, the legs being substantially parallel and the upwardly directed arms being directed towards a plane common to the longitudinal axes of both legs.
